UNITED STATES PATENT OFFICE

WILLIAM O. T. WATKINS, OF LITTLE ROCK, ARKANSAS

SLIDE FOR PLAYGROUNDS

Application filed June 14, 1927. Serial No. 198,835.

My invention relates to slides for playgrounds. It has for its object to provide a construction whereby greater safety to children using the slide is provided, and the children are prevented from practicing the hazardous sport commonly known as "skinning the cat" and which frequently results in serious accidents to the children practicing that sport on the slides very generally to be found on school playgrounds.

To the accomplishment of the foregoing and such other objects as may hereinafter appear, the invention consists in the features hereinafter particularly described and then sought to be clearly defined by the claim, reference being had to the accompanying drawing forming a part hereof, and in which

Figure 1 is a perspective view of a playground slide embodying the invention; 20 Figure 2 is a cross-section on the line 2—2 of Fig. 1.

In the drawing the numeral 1 designates the runway of the slide; 2 the steps or stair-case leading to the platform at the top of the run-way; 4 the bracing frame for the steps and run-way; 5 the hand rails at opposite sides of the stair-case, and 6 the side hand rails to the platform, said side rails 6 being braced by the upright brace rods 7 rising from the upper end of the run-way or the platform at the top thereof. The parts above specified may be of any approved type of construction and constituting in general the playground slide in very general use.

In order to prevent children grasping the side rails of the platform, swinging forward beyond the ends of the rails and dropping onto the run-way and thus incurring the evil results of sudden shock, and possible injury to the spine, the side rails, at their ends, may be joined one to the other by a cross-rail 8 which will necessitate the child stooping to pass beneath the cross-rail in order to reach the run-way and in that way dropping onto the run-way by a swinging jump is prevented and possible injury to the child guarded against.

With such cross-guard rail or bar, however, the inclination of the child is to "skin the cat" as it is commonly termed and this is

likely to result in kicking or striking the child following the one in the lead, as well as being calculated to result in some injury to the child indulging in that particular sport. With the view of preventing that sport being indulged in on the slide, I provide back of the forward ends of the side rails to the platform an arched or bowed member 9, rising above the side rails which provides an obstruction in the path of the swing of the body and legs in making the circle or somersault involved in "skinning the cat" and thus the child is prevented indulging in that particular sport on the slide and the consequent dangers guarded against. This bowed or arched member may be connected to the side rails 6, or to the upright brace rods 7 in any suitable manner, the preferred means being by couplings 10 of appropriate formation for connecting the ends of the arch member to the side rails or upright brace rods as illustrated, although any other suitable coupling means as may come within mechanical skill may be used for the purpose

I have illustrated and described the preferred embodiment of my invention but it is to be understood that changes can be made therein without departing from the scope of the invention as sought to be defined by the appended claim.

Having described my invention and set forth its merits, what I claim is:—

A slide for playgrounds comprising an inclined run-way having a platform at its upper end, side hand rails at the upper part of the run-way and projecting beyond the platform, a cross-rod connecting together the forward portions of the hand rails at a point beyond the forward edge of the platform, and an arched member connected to the hand rails and spanning the space between the rails.

In testimony whereof I affix my signature.

WILLIAM O. T. WATKINS.
